UNITED STATES PATENT OFFICE.

ORLANDO E. KELLUM, OF LOS ANGELES, CALIFORNIA.

AUTOMATIC SOUND CONTROL FOR PHONOGRAHS AND THE LIKE.

Application filed September 18, 1920. Serial No. 411,215.

To all whom it may concern:

Be it known that I, ORLANDO E. KELLUM, a citizen of the United States, residing at Los Angeles, county of Los Angeles, State 5 of California, have invented new and useful Improvements in Automatic Sound Controls for Phonographs and the like, of which the following is a specification.

This invention relates to an automatic 10 sound control for a phonograph and is particularly adapted for embodiment in connection with a phonograph which is arranged to operate in synchronism with other mechanism, such, for instance, as a kinetograph.

In a broad and general way the invention 15 relates to and comprises an automatic sound control for a phonograph, musical instrument, or, in fact, any mechanism or apparatus similar or equivalent to a phonograph or 20 musical instrument. In the present form of the invention I provide means, embodying electrical and mechanical means, for carrying out the invention in a manner that can be advantageously employed when the invention 25 is applied to a phonograph. In this particular means I provide a mechanical modifying or dampening device in connection with the sound arm of the phonograph, electromagnetic means for operating the 30 modifying device, and adjustable control means for the electro-magnetic means. In operation the sound from the phonograph is partially or completely cut off at the desired time or times and is unmodified in any 35 way at other times.

In a somewhat more specific sense the invention comprises in combination two synchronously operating mechanisms, one of 40 which is a phonograph, and automatic sound control for the phonograph. To disclose this phase of the invention I am herein setting forth a synchronous phonograph and kinetograph with the automatic sound control device in connection with the phonograph. 45 In such an arrangement as this the control means in the automatic sound control device can be actuated by the phonograph, or by the kinetograph, either of which will cause it to operate in synchronism with both the 50 phonograph and kinetograph and thereby cause synchronous operation of the entire combined apparatus.

This last mentioned phase of the invention is of particular note and importance from a 55 practical standpoint in that it provides, in combination with a synchronous phonograph

and kinetograph, means for controlling the sound produced by the phonograph in such manner as to either completely cut it off or to modify it. In practice when a phonograph 60 and kinetograph are operating synchronously there are times when it is desired to modify the sound produced by the kinetograph and there are times when it is desired to completely cut off all of the sound from 65 the phonograph. In operation the present invention effectively and automatically produces the desired modification and cutting off of the sound; and, in fact, when it operates to completely cut off the sound it positively 70 cuts off all of the sound even that caused by the operation of the phonograph mechanism, including the needle scratch, etc. Such operation as this cannot be had by any sort of recording on the record used on 75 the phonograph. For instance, in the ordinary operation of the phonograph when it is playing a part of the record on which no musical or vocal sounds have been recorded, such as the starting blank groove or any intermediate blank portion, the needle scratch and sound from the operating mechanism are all that pass through the horn and are therefore noticeably perceptible and are 80 objectionable.

Other objects and features of the invention will be best understood from the following detail description of a preferred embodiment of the invention throughout which reference is had to the accompanying drawings, in which—

Fig. 1 is a plan view of an apparatus embodying a phonograph kinetograph and the automatic sound control device for the phonograph; Fig. 2 is an enlarged detail sectional view taken as indicated by line 2—2 95 on Fig. 1; and Fig. 3 is an enlarged side elevation of a portion of the automatic sound control device showing the electric circuits diagrammatically.

In the drawings numeral 10 designates a typical phonograph mechanism in connection with which is arranged a typical kinetograph mechanism 11. The phonograph mechanism 10 is adapted to be operated by 105 a motor 12 directly connected with the record carrying table 13, while the kinetograph mechanism 11 is adapted to be operated by a motor 14. The motor 14 is synchronous electric motor operated from and 110 controlled by a commutator mechanism 15 operated from and by the phonograph mech-

anism 10. In practice the commutator mechanism 15 is operated by a shaft 16 which is directly connected to and rotated by the mechanism which connects the motor 12 and 5 record-carrying table 13. The commutator mechanism 15 and motor 14 are so constructed and connected that the phonograph mechanism 10 and kinetograph mechanism 11 will operate in perfect synchronism. The 10 commutator mechanism 15 and motor 14, which it may be said is the means for synchronously connecting the phonograph mechanism and kinetograph mechanism, may be and preferably are of the character set forth 15 in my copending application entitled "Synchronous motor systems," filed Aug. 19, 1920, Serial No. 404,684. It will be understood, however, that the nature of the present invention is such that it is not in any way 20 limited or restricted to any one particular or specific means for synchronously connecting the phonograph mechanism and kinetograph mechanism. Further it may be here stated that various forms and types of phonograph 25 mechanisms and kinetograph mechanisms may be used in carrying out the invention without in any way departing from the spirit thereof.

As means for dampening off or regulating 30 the sounds from the phonograph mechanism 10 a damper or valve 18 is arranged in connection with the sound arm 19 of the phonograph mechanism. I am showing the regulating means, or in other words the 35 valve 18, in connection with the sound arm 19 merely because it may be easily and effectively arranged at that part of the phonograph mechanism, it being understood of course that it might well be arranged in or 40 at any sound transmitting portion of the phonograph mechanism. Guides 20 are provided on the sound arm 19 to slidably carry the valve 18 and direct it in various movements. The valve 18 itself is a member, or structure, having a closed or continuous portion 21 and an opening or aperture 22. The continuous portion of the valve 18 is of sufficient size to completely 45 cut off or close off the sound arm, in the manner clearly shown in Fig. 2 of the drawings, while the opening 22 in the valve is the same size as the opening in the sound arm and is adapted to register with the opening in the sound arm under certain 50 operating conditions. In the particular form of the invention herein set forth the continuous portion of the valve is at the upper end thereof while the opening 22 is formed at the lower end thereof. It is obvious that when the valve 18 is in the position 55 shown in Fig. 2 that the sound arm is completely closed in a manner to positively prevent the passage of sounds, of any kind, through it, and that when the valve is in a 60 position to cause the opening 22 to register

with the opening in the sound arm that the sound arm is unrestricted and will allow free passage of sounds through it, and that when the valve is in a position intermediate of the above mentioned positions that the sound 70 arm will be cut off or restricted to a more or less degree depending upon the particular positioning of the valve, thereby partially restricting the passage of sound through the arm.

To operate the valve 18 it is connected to or with a solenoid mechanism 25. The solenoid mechanism 25 is mounted on the sound arm 19 by a suitable member 26 and comprises, generally, three concentric coils 27 arranged so that there is a vertical opening 28 through them. A core 29 is freely carried in the opening 28 so that it will be moved through the opening 28 by energization of any of the coils. The core 29 is connected 80 to the valve 18 by a suitable rod 30 thereby causing the valve 18 to be operated when the core 29 is moved. In the preferred form of construction the valve 18 and rod 30 are of light construction and a light spring 90 31 is connected to a bracket 32 which extends downwardly through the opening 28 and connects to the core 29. In practice the spring 31 is not sufficiently strong to support the load of the core 29, rod 30, and valve 18, 95 although it is of such strength as to almost counterbalance the weight of these parts, thereby allowing the core 29 to be very easily moved by the coils 27. It will be readily understood how energization of any 100 one of the coils 27 will cause the core 29 to be moved through the opening 28 until it is within that particular coil. For instance, if the core 29 is in the position shown in Fig. 2 and the lowermost coil 27 is energized, 105 the core will move only a short distance upwardly through the opening 27, thereby causing only slight opening of the valve 18. If the central coil 27 is energized the core 29 will move through the opening 28 until 110 it is within the central coil 27, or equidistant between the top and bottom coils 27, thereby causing the valve 18 to be in a half-open position. If the uppermost coil 27 is energized the core 29 will be moved to its extreme upper position, causing the opening 22 in the valve 18 to register with the opening in the sound arm 19, thereby causing the 115 passage of sound to be unrestricted. At such times when none of the coils 27 are 120 energized the core 29 is moved downwardly in the opening 28 by gravity until it engages the stops 34, in the manner clearly shown in Fig. 2. When the core 29 is in this last 125 mentioned position the valve 18 is in position to cause the sound arm to be completely and entirely cut off.

As means for automatically controlling the energization of the coils 27 a commutator mechanism 40 is arranged in the electrical 130

circuit in which the coils 27 are arranged. The commutator mechanism 40 comprises three metal disk-like members 41 mounted on a shaft 42 which is rotated or driven from the shaft 16 through a cooperating worm 43 and worm-gear 44 mounted on the shaft 16 and shaft 42 respectively. Each of the members 40 is formed at its periphery with a plurality of tapped holes 45 which are adapted to receive screws 46 by which contact plates 47 are secured to the members 41. By providing a plurality of holes 45 in the member 41 it is possible to very easily and conveniently arrange various numbers and sizes of contacts 47 on the members 41. A brush holder 48, preferably formed of insulating material, carries three brushes 49, each adapted to cooperate with one of the members 41. The brushes 49 are constructed so that they will not actually engage the members 41, although they will engage and make good electrical contact with the contacts 47. A wire 50 leads from one side of the source of electrical energy 51 to the shaft 42 on which the members 41 are mounted. Wires 52 lead from the brushes 49 to the other side of the source of electric energy and have the coils 27 arranged in them in a manner clearly shown in Fig. 3. It will be readily understood how, when one of the members 41 is moved so that one of the contacts 47, mounted on it, engages one of the brushes 49, an electrical circuit is completed from the source of electrical energy 51, through the wire 50, through the shaft 42, through the plates 41, through the contact and brush, which are in engagement with each other, through the wires 52, which connects to that brush, and through the coils 27 arranged in the wires 52. It is obvious, that when the members 41 are rotated in synchronism with the phonograph mechanism in a manner such as has been hereinabove described, and have contacts 47 of various sizes arranged in proper intervals on them so that the several units of the solenoids, or the coil 27, and therefore the valve 18, will operate at the proper and desired time or times. It may be said that the mechanism just described provides an adjustable automatic means for actuating the valve 18 and that the mechanism just described may be synchronously operated with the other mechanisms in any suitable or desired manner and is not necessarily limited to being operated in the specific manner herein set forth. It is obvious that various numbers of members 41 may be employed with various arrangements or forms of the solenoid mechanism, and that permanent or fixed member 41, that is members with fixed contacts 47, may be provided or made to be used with certain phonograph records. In other words, each phonograph record may be supplied with a member 41 which is made par-

ticularly for it. Further it may be pointed out that the means for operating the valve 18, which in this case is the solenoid mechanism 25, may be constructed to operate or move the valve 18 to any number of various positions and that it is in no way limited to a three unit device such as has been hereinabove described. However, in connection with the particular three unit solenoid mechanism herein set forth it will be noted that it is possible to move or actuate the core 29 and therefore the valve 18 to more positions than there is number of coils 27. For instance, if any adjacent coils 27 are energized, the core 29 will be moved by the combined force of the two coils, and therefore will not be in a position such as would be caused by either of the coils 27 singly.

Having set forth only a preferred embodiment of the invention I do not wish to restrict myself to the specific details hereinabove set forth, but wish to reserve to myself any variations that may appear to those skilled in the art and that may fall within the scope of the following claims.

Having described a preferred form of my invention, I claim:

1. In combination with the sound generating apparatus and the sound conducting passage of a phonograph, a valve in the passage for regulating the passage of sound, electro-magnetic means for actuating the valve, and a commutator mechanism for controlling the energization of the electro-magnetic means operated in synchronism with the sound generating apparatus.
2. In combination with the sound generating apparatus and the sound conducting passage of a phonograph, a valve in the passage for regulating the passage of sound, a plurality of electromagnetic units adapted to be energized independently or in groups to actuate the valve, and means operating in synchronism with the sound generating apparatus for controlling the energization of the units.
3. In combination with the sound generating apparatus and the sound conducting passage of a phonograph, a valve in the passage for regulating the passage of sound, a plurality of electro-magnetic units adapted to be energized independently or in groups to actuate the valve, and a commutator mechanism operating in synchronism with the sound generating apparatus for controlling the energization of the several units.
4. In combination with the sound conduct of a phonograph, a valve in the conduct adapted to be actuated to regulate the passage of sound through the conduct, the valve being arranged so that it is actuated in one direction by gravity, a plurality of electro-magnetic units each adapted when energized to actuate the valve to a different position and means for energizing the electro-mag-

netic units independently or in groups to actuate the valve in the other direction to various positions.

5. In combination with the sound generating apparatus and the sound conducting passage of a phonograph, a valve in the passage for regulating the passage of sound, a plurality of electro-magnetic units adapted to be energized independently or in groups to actuate the valve, and a commutator mechanism operating in synchronism with the sound generating apparatus for controlling the energization of the several units, the commutator mechanism including a moving carrier, a plurality of contacts detachably adjustably mounted on the carrier, and a stationary contact adapted to cooperate with the contacts mounted on the carrier.

6. In combination with the sound conduct of a phonograph, a valve in the conduct adapted to be actuated to regulate the passage of sound through the conduct, the valve being arranged so that it is actuated in the direction by gravity, the valve having a stem projecting from the conduct, electro-magnetic means for actuating the valve in the other direction including a core attached

to the stem of the valve, and a spring in connection with the core tending to move it and the parts connected with it against the resistance of gravity.

7. In combination with the sound generating apparatus and the sound conducting passage of a phonograph, a valve arranged in the passage to regulate the passage of sound, the valve being arranged so that it is actuated in one direction by gravity, a spring in connection with the valve to tend to move it against the resistance of gravity but not strong enough to move it, a plurality of electro-magnetic units adapted to be energized independently or in groups to actuate the valve in the other direction, to various positions, and a commutator for controlling the energization of each unit, the commutators being connected with the sound generating apparatus to operate in synchronism therewith.

In witness that I claim the foregoing I have hereunto subscribed my name this 8th day of September, 1920.

ORLANDO E. KELLUM.

Witness:

VIRGINIA BERINGER.
